ABSTRACT

A nozzle for insertion into the central opening of a nozzle seat in a pouring ladle has a stationary member and a rotatable member. The stationary member is secured within the central opening of the nozzle seat and has a closed upper surface, a central passageway and a plurality of spaced openings communicating with the central passageway. The rotatable member is positioned within the central passageway of the stationary member to define an annular gap therebetween. The rotatable member also has a plurality of spaced channels leading to a central aperture so upon rotation of the rotatable member, the openings of the stationary nozzle and the channels of the rotatable member are aligned to provide a continuous exit for liquid from the ladle. An inert gas is directed into the gap to prevent liquid metals from entering therein and also to lubricate the system.

NOZZLE FOR A POURING LADLE

This invention relates to a stopper arrangement for a pouring ladle and, more particularly, to the nozzle itself.

Heretofore, the metals industry, primarily the steel industry, has employed an antiquated stopper rod assembly for opening and closing the exit passageway from a pouring ladle containing liquid metal. This stopper rod assembly, as employed heretofore, utilizes a nozzle held in place by a nozzle plate mounted to the bottom of the ladle and secured in place by a cementitious refractory rammed between the nozzle and the well area in the bottom of the ladle. A long refractory-wrapped steel rod called a stop rod vertically extends within the ladle and is connected to a cross member called a gooseneck above the top of the ladle. The bottom of the stopper rod has a refractory nozzle head mounted thereon to cooperate with the nozzle to open and close the nozzle opening. A cumbersome hydraulic cylinder arrangement is positioned on the outside of the ladle and is connected to the gooseneck to raise and lower it, thus serving as the control for opening and closing the nozzle.

Not only is the above-described system cumbersome, but after every pour a crew of men must climb into the ladle after it is cooled to reset the next nozzle. In addition, many numerous problems result from attempting to maintain the long stopper rod in proper position so that the nozzle head fits snugly into the nozzle central opening. Any form of misalignment causes improper shut-offs and leaky pours.

With the advent of continuous casting which employs an intermediate ladle called a tundish, the requirements for precise pouring control has increased, thereby increasing the need for improved stopper assemblies.

My invention eliminates the stopper rod assembly as known heretofore, thereby eliminating the inherent problems associated with it. Further, my invention can be substantially preassembled thereby avoiding many of the time-consuming, nozzle setting efforts required in the past. Since my invention employs a gap between coaxing members, normal expansion and contraction is easily accommodated. Because the control of my nozzle is direct, all the many problems associated with indirect control are eliminated thereby permitting a better feel on the part of the operator to provide a more accurate and efficient shut off.

My invention is a nozzle which comprises a stationary and a rotatable member. The stationary member is secured within the bottom opening of the ladle, that is, in the well or nozzle seat. The stationary member has a closed upper surface and a series of openings leading to a central passageway. The rotatable member is positioned within the stationary member to form a gap therebetween. The rotatable member also has a plurality of channels leading to a central aperture so that rotation thereof permits alignment of the openings and channels to exit the liquid metal from the ladle. An inert gas is directed into the gap to lubricate the system and to prevent metal from entering therein.

In the accompanying drawings, I have shown the presently preferred embodiments of my invention in which:

FIG. 1 is a vertical section through my nozzle, showing the nozzle in the open position;

FIG. 2 is a section taken along line II-II of FIG. 1;

FIG. 3 is a break away section showing the nozzle in closed position;

FIG. 4 is a section taken along line IV-IV of FIG. 3;

FIG. 5 is a section taken along line V-V of FIG. 1; and

FIG. 6 is a vertical section showing a modified gap arrangement.

My nozzle, generally designated 10, is employed with a variety of types of ladles which contain molten metal. It will be recognized by those skilled in the art that this includes, but is not limited to pouring ladles, transfer ladles, tundishes and, in general, any form of ladle wherein a liquid metal is contained therein for purposes of pouring and exiting therefrom. My nozzle 10 is secured in the bottom of the ladle in a nozzle seat 11. This nozzle seat 11 is a refractory which has a central

opening and which is secured in the bottom well of the ladle and is held in place by cementitious material as well as a nozzle plate affixed to the bottom of the ladle and not shown.

5 My nozzle 10 includes a stationary member 12 and a rotatable member 14, see FIG. 1. The stationary member 12 is secured within the opening of the nozzle seat 11 and is held in place by a cementitious material 13 between the stationary member 12 and the nozzle seat 11. It will be recognized that the nozzle plate (not shown) can also be employed to aid in the 10 securing and the holding of the stationary member 12 within the central opening of the nozzle seat 11.

The stationary member 12 is annular and has a central 15 passageway 15 extending from a closed, dome-shaped upper surface 16 downward therethrough. A plurality of spaced

15 openings 17 extend through the stationary member 12 and communicate with the central passageway 15. I have shown four such openings 17 in the particular embodiments depicted in the figures, but it will be recognized that more or less 20 openings can be employed. These openings 17 are positioned just above the nozzle seat 11, within the interior of the ladle and are inclined downward into the central passageway 15.

The stationary member extends down through the opening 25 of the nozzle seat 11 and below the bottom of the ladle, not shown. As will be explained in detail hereinafter, the stationary member 12 may be a single component or may be two separate components integrally connected.

The rotatable member 14 is also annular and is positioned 30 within the central passageway 15 of the stationary member 12.

30 The cross section of the rotatable member 14 is slightly smaller than the cross section of the central passageway 15 so that a narrow gap 18 is defined by the outer surface of the rotatable member 14 and the surface of the stationary member 12 which defines the central passageway 15. The 35 rotatable member 14 also has a central aperture 19 which extends vertically completely therethrough.

The rotatable member 14 has a plurality of channels 20 40 leading through the rotatable member 14 into the central aperture 19. The number of channels 20 will be the same as the number of openings 17 in the stationary member since, as will be described hereinafter, the channels 20 are aligned with the openings 17 by rotation of the rotatable member 14 to permit exit of the liquid from the ladle through and out of the central aperture 19, see FIG. 2. The channels 20 are also inclined

45 to form a continuous axial alignment with the openings 17.

The rotatable member 14 is maintained within the central 50 passageway 15 of the stationary member 12 by a bottom plate 21 of appropriate material such as steel which is secured to the bottom of stationary member 12 by standard fastener means

55 22. A biasing means such as spring 23 is positioned between the bottom plate 21 and the rotatable member 14 to urge the rotatable member 14 upward toward the inner surface of domed surface 16 to maintain the appropriate axial alignment

of the openings 17 and channels 20. As shown in FIG. 1, the 60 springs 23 are positioned in a cutaway portion of rotatable member 14, although this could easily be a bottom recess or other similar type arrangement in rotatable member 14. It is important that the springs 23 are maintained apart from any molten metal and, therefore, the springs must be displaced

65 from the area of the central aperture 19.

The gap 18 extends from at least the aligned openings 17 and channels 20 downward to a point below the bottom of the ladle. The gap 18 terminates at a packing material 24 such as

65 asbestos which is between the stationary member 12 and the rotatable member 14 to completely seal off the bottom of the gap 18 to prevent any leakage therefrom. A duct 25 extends through the stationary member 12 into the bottom area of the gap 18. Duct 25 has an internally threaded inlet connection 26

70 to permit a standard hose connection to be made thereto. An inert gas such as argon is directed through duct 25 into gap 18 to lubricate the system and prevent liquid metal from entering the gap. The inert gas then bubbles through the molten metal

75 and acts as a purge which will improve the internal characteristics of the final product. The inert gas is prevented from

escaping from the bottom of the gap 18 by the packing material 24.

The portion of the stationary nozzle member 12 below the packing material 24 can be a continuous extension of a single component or can be a separate integrally connected component 27, as shown in FIG. 1 wherein annular connecting ring 30 threadably engages the upper component 12 and the lower component 27 to form the integral connection. In either event, the lower portion of stationary member 12 contains a horizontal slot 28 of sufficient length to permit a lever 29 to be inserted therethrough and into threadable engagement with a suitable recessed receiving means in rotatable member 14 to permit rotation thereof to open and close the alignment of channels 20 with openings 17, see FIG. 5.

The operation of my nozzle is as follows. While the ladle is being filled with molten metal, the rotatable member 14 is in position with respect to the stationary member 12 so that the channels 20 are not aligned with the openings 17, see FIGS. 3 and 4. The inert gas such as argon is directed into gap 18 and out through openings 17 into the molten metal to create a purge thereof. When it is desired to pour the molten metal, the lever 29 is turned until the channels 20 are in alignment with the openings 17, see FIGS. 1 and 2, thereby permitting the molten metal to exit from the ladle through the central aperture 19 of rotatable nozzle member 14. It can be seen that since the lever contact is direct to the rotatable member 14, exacting control of the pouring stream can be maintained. It will be recognized that various mechanized means may be employed to rotate the rotatable member 14 instead of lever 29 which is intended for manual operation.

Because of the necessity of maintaining a continuous high pressure flow of inert gas in the gap 18, the gap may be modified in the vicinity of the openings 17. Such an arrangement is shown in FIG. 6 in which like parts to earlier described components are similarly numbered, but are followed by a prime. The surfaces 30 and 31 of stationary member 12' and rotatable member 14', respectively, which define the gap 18' are recessed so that the major portion of 18' has an enlarged cross section as compared to the cross section of 18' in the vicinity of the openings 20' and channels 17'. In other words, this decrease in cross section causes restricted flow thereby increasing the pressure to keep the molten metal from entering gap 18'. It should be noted that in FIG. 6 the stationary member 12 is shown as one continuous component above and below the packing 24' which is positioned immediately below gap 18'.

While I have shown and described preferred embodiments of my invention, it may be otherwise embodied within the scope of the appended claims.

I claim:

1. A nozzle for insertion into the central opening of a nozzle seat in a pouring ladle comprising:
  - A. a stationary nozzle member secured within the central opening of the nozzle seat and having a closed upper surface, a central passageway extending downward from said closed upper surface, a plurality of spaced openings therethrough, said openings positioned adjacent the closed upper surface and communicating with the central passageway and a duct therethrough positioned substantially below the spaced opening and also communicating with the central passageway;
  - B. a rotatable nozzle member positioned within said central passageway and extending downward from above said plurality of spaced openings to define an annular gap between said stationary and rotatable nozzle members, said gap extending from said plurality of spaced openings at least to said duct, said rotatable nozzle member having a central aperture therethrough and a plurality of spaced channels adapted upon rotation of said rotatable nozzle member to align with the openings of said stationary nozzle member to permit rotation thereof;

zle member to provide a continuous exit for liquid from the ladle out of the central aperture; and

C. means secured to said rotatable nozzle member to permit rotation thereof.

5 2. The nozzle of claim 1 wherein the plurality of spaced openings and the plurality of spaced channels are inclined downwardly into the central passageway and central aperture, respectively.

10 3. The nozzle of claim 1 wherein packing means are positioned between the rotatable nozzle member and the stationary nozzle member at the bottommost portion of said gap.

4. The nozzle of claim 1 wherein biasing means are positioned at the bottom of said rotatable nozzle member to urge said rotatable member upward.

15 5. The nozzle of claim 1 wherein the surface of the stationary and rotatable nozzle members which define said gap are recessed respectively to form a gap of relatively large cross section substantially along the gap's length and terminating at the gap's upper end in a restricted gap of relatively small cross section.

20 6. The nozzle of claim 1 wherein said rotation permit means is a lever threadably secured to said rotatable nozzle and extending through a slot in said stationary nozzle.

25 7. The nozzle of claim 2 wherein said plurality of inclined openings comprises four equally oriented and spaced openings and said plurality of inclined channels comprises four equally oriented and spaced channels.

30 8. The nozzle of claim 3 wherein said stationary nozzle member includes two separate components and a connecting means integrally connecting said components, the stationary nozzle member above the packing being the first component and the stationary nozzle member below the packing being the second component, said spaced openings and duct being in the first component and said means to rotate extending through a slot in said second component.

35 9. The nozzle of claim 4 wherein an annular bottom plate is secured to the bottom of the stationary nozzle member to act as the bottom support for said biasing means.

40 10. In combination with a pouring ladle, a stopper assembly comprising:

A. a nozzle seat positioned in the exit hole of the pouring ladle and having a central opening therethrough;

B. a stationary nozzle member secured within the central opening of the nozzle seat and having a closed upper surface, a central passageway extending downward from said closed upper surface, a plurality of spaced openings therethrough adjacent said closed upper surface and communicating with the central passageway and a duct therethrough positioned substantially below the spaced opening and also communicating with the central passageway;

C. a rotatable nozzle member positioned within said central passageway and extending downward from above said plurality of spaced openings to define an annular gap between said stationary and rotatable nozzle members, said gap extending from said plurality of spaced openings at least to said duct, said rotatable nozzle member having a central aperture therethrough and a plurality of spaced channels adapted upon rotation of said rotatable nozzle member to align with the openings of said stationary nozzle member to provide a continuous exit for liquid from the ladle out of the central aperture;

D. a packing means positioned between the rotatable nozzle member and the stationary nozzle member at the bottommost position of said gap;

E. a biasing means positioned at the bottom of said rotatable nozzle member to urge said rotatable member upward; and

F. means secured to said rotatable nozzle member to permit rotation thereof.
